D8-347.

OR D11,794

EX

No. 11,794

June 1, 1880

UNITED STATES PATENT OFFICE.

GEORGE S. BARKENTIN, OF NEW BRITAIN, CONNECTICUT, ASSIGNOR TO P.
AND F. CORBIN, OF SAME PLACE.

DESIGN FOR KEY-BOW.

SPECIFICATION forming part of Design No. 11,794, dated June 1, 1880.

Application filed March 29, 1880. Term of patent 7 years.

To all whom it may concern:

Be it known that I, GEORGE S. BARKENTIN, of New Britain, in the county of Hartford and State of Connecticut, have originated and produced a Design for Key-Bows, of which the following is a specification.

The accompanying wood-engraving sufficiently represents my design, in which A is the bow, B the shank or stem, and C the bit. The bow A is made angular at the top, the sides are slightly curved inward, and the bottom or base is made straight. Above the base, on the flat surface of the bow, are three perforated ornaments, as shown in the drawing.

The shank and bit may be of any suitable form to adapt it to the purpose required—as, for instance, the shank may be flat or oval, and the bit of varying size and shape for a door or cabinet lock.

I claim as my invention—

The design of the key-bow A, substantially as shown and described.

Signed by me this 22d day of March, 1880.

GEORGE S. BARKENTIN.

In presence of—

CHARLES E. WETMORE,
E. L. PRIOR.
